CLAIM

The ornamental design for a bag as shown and described.

DESCRIPTION

FIG. 1 is a front, right-side elevational view of a bag, showing the new design;

FIG. 2 is a front elevational view thereof; and

FIG. 3 is a rear elevational view thereof;

FIG. 4 is a left-side elevational view thereof;

FIG. 5 is a right-side elevational view thereof;

FIG. 6 is a top plan view thereof;

FIG. 7 is a bottom plan view thereof; and,

FIG. 8 is a front elevational view of the bag of FIG. 1 in a closed state.

The broken lines depict parts of the bag that form no part of the claimed design.

1 Claim, 8 Drawing Sheets(56)
